(57) **CLAIM**

The ornamental design for a set of slatwall panels, as shown and described.

DESCRIPTION

FIG. 1 is a front perspective view of a first embodiment of a set of slatwall panels according to our design;

FIG. 2 is a front view of the set of slatwall panels of FIG. 1;

FIG. 3 is a rear view of the set of slatwall panels of FIG. 1; FIG. 4 is a top view of the set of slatwall panels of FIG. 1; FIG. 5 is a bottom view of the set of slatwall panels of FIG. 1;

FIG. 6 is a left view of the set of slatwall panels of FIG. 1; FIG. 7 is an enlarged view of portions of the set of slatwall panels of FIG. 6, the portions identified by window 7 in FIG. 6;

FIG. 8 is a right view of the set of slatwall panels of FIG. 1; FIG. 9 is a front perspective view of the set of slatwall panels of FIG. 1 assembled in a first position to define a panel assembly;

FIG. 10 is a front perspective view of the set of slatwall panels of FIG. 1 assembled in a second position to define a panel assembly;

FIG. 11 is a front perspective view of a second embodiment of a set of slatwall panels according to our design;

FIG. 12 is a front view of the set of slatwall panels of FIG. 11;

FIG. 13 is a rear view of the set of slatwall panels of FIG. 11;

FIG. 14 is a top view of the set of slatwall panels of FIG. 11; FIG. 15 is a bottom view of the set of slatwall panels of FIG. 11;

FIG. 16 is a left view of the set of slatwall panels of FIG. 11; FIG. 17 is an enlarged view of portions of the set of slatwall panels of FIG. 16, the portions identified by window 17 in FIG. 16;

(Continued)

FIG. 18 is a right view of the set of slatwall panels of FIG. 11;
 FIG. 19 is a front perspective view of the set of slatwall panels of FIG. 11 assembled in a first position to define a panel assembly;
 FIG. 20 is a front perspective view of the set of slatwall panels of FIG. 11 assembled in a second position to define a panel assembly;
 FIG. 21 is a front perspective view of a third embodiment of a set of slatwall panels according to our design;
 FIG. 22 is a front view of the set of slatwall panels of FIG. 21;
 FIG. 23 is a rear view of the set of slatwall panels of FIG. 21;
 FIG. 24 is a top view of the set of slatwall panels of FIG. 21;
 FIG. 25 is a bottom view of the set of slatwall panels of FIG. 21;
 FIG. 26 is a left view of the set of slatwall panels of FIG. 21;
 FIG. 27 is an enlarged view of portions of the set of slatwall panels of FIG. 26, the portions identified by window 27 in FIG. 26;
 FIG. 28 is an enlarged view of portions of the set of slatwall panels of FIG. 26, the portions identified by window 28 in FIG. 26;
 FIG. 29 is a right view of the set of slatwall panels of FIG. 21;
 FIG. 30 is a front perspective view of the set of slatwall panels of FIG. 21 assembled in a first position to define a panel assembly; and,
 FIG. 31 is a front perspective view of the set of slatwall panels of FIG. 21 assembled in a second position to define a panel assembly.
 The drawings contain a symbolic break. The portion between the break lines forms no part of the claimed design. The dash-dash broken lines in the figures depict portions of the set of slatwall panels that form no part of the design. The dash-dot-dash broken lines represent boundaries of the claimed design and form no part thereof. The dot-dot-dash broken lines represent boundaries of the enlarged views and form no part of the claimed design.
